UNITED STATES PATENT OFFICE.

JOSEPH E. TWITTY, OF JACKSONVILLE, FLORIDA.

PORTABLE SECTIONAL REFRIGERATOR.

Application filed May 24, 1927. Serial No. 193,852.

My present invention relates to certain new and useful improvements in sectional or unit type refrigerators, composed of interchangeable standard sections adapted to be regularly 5 assembled to provide varying refrigerating space.

My invention contemplates the production of a refrigerator by the assembling of the desired number of wall sections or units in combination with the insulated top and bottom members in size corresponding to the contemplated size of the refrigerator.

One important feature of my invention relates to the manner of assembling the cork or 15 insulating material in the frames of the side wall units, so as to enable the side walls to present a continuous insulation, which moreover is adapted to form a lap joint with the insulation of the top and bottom, thus providing the refrigerator throughout with a continuous butt joint insulating lining. An advantage of this construction is that the framework is protected from such a variation in 20 temperature as will cause it to sweat. I am enabled to provide a refrigerator with a lining especially suited to receive a cement plaster coating extending continuously about the entire surface of the refrigerator, and which, being supported wholly by the flexible insulation, is free to expand and contract without cracking.

A further important feature of my invention lies in the very simple and effective manner in which I attain the necessary confined 35 air space between the inner insulation and outer radiating surface of the refrigerator. This I accomplish by mounting the insulation so that it projects inwardly beyond its supporting frame a distance substantially corresponding to the width of the confined air 40 space, thereby permitting the outer radiating surface to be attached to the outer surface of the frame, and providing a simple and economical construction of the wall units.

My invention further comprises novel details of construction and arrangement of parts, which in their preferred embodiment only are illustrated in the accompanying drawings, which form a part of these specifications, and in which Figure 1 is a view showing my typical refrigerator partly in elevation and partly in vertical cross-section. Figure 2 is a fragmental cross-sectional plan view of one corner of the refrigerator. Figure 3 is a sectional view showing one of the side wall sections with fragmental views of

co-related side and corner sections. Figure 4 is a detail perspective view of one of the standard wall sections. Figure 5 is a detail view showing the key lock for the frame sides 60 and the joint made by the groove strip with the bottom plate.

Throughout the drawings, corresponding numerals refer to corresponding parts.

In the embodiment of my invention illustrated, and which will be understood as typical of any size or type of refrigerator, I have shown a portable sectional refrigerator composed of a bottom frame or plate (5) corresponding substantially to the horizontal cross-sectional dimensions of the refrigerator, and which receives and confines within it the sections of cork or like insulation (6) which, as will be seen in Figure 1, project substantially above the upper wall of the plate, and which rest on the foundation or support for the refrigerator. The top of the refrigerator is formed by a frame or plate (7), similar to (5), and which receives the sections of cork or insulation (8) which project substantially below the bottom level of the plate. These cork sections are attached to ceiling joists (9) or equivalent bars, resting upon the top plate (7), and serving to support the cork or insulation firmly in place.

The side walls of the refrigerator are formed by a plurality of duplicate units, except the door which is illustrated conventionally at (10) being mounted by hinges (11) to its door section, which preferably occupies the space of a wall section. The duplicate sections, all of which are alike, comprise a marginal frame (12), formed of wood, metal, or any suitable material. In the drawing I show a frame formed of wood, framing $2\frac{1}{4}$ by $3\frac{3}{4}$. This frame has a width corresponding to the length of the standard cork board, and in height equal to any desired multiple of the cork boards or a fraction thereof. The sections of cork board (13) are set in this frame against a stop strip (14) nailed on its inside at the desired distance from the outer surface of the frame. The distance that the inner face of the stop strip is set from the outer surface of the frame determines the size of the confined air space (15) which is to be provided between the cork and the outer surfacing (16), which may be of any suitable material, such for instance, as any standard stucco or plaster receiving board, metal lath, or the like, which is adapted to be attached to the outer surface

of the frame, thus completing the side wall unit.

Each side wall section has its vertical frame walls adapted to abut the corresponding frame wall of the adjacent aligning section, or at the corners to abut the corner post (17). Lag screws (18) serve to connect the wall unit frames to the adjacent corner posts and wedge keys (19) are adapted to be driven into 10 the corresponding sockets to interlock the abutting sides of the frames, one to another, thus rigidly assembling the side wall sections to each other, and to the corners.

I insert cork filler strips (20) to fill in the 15 space between the cork or insulation in the adjacent side units and to insulate the abutting side walls of the frame. In completing the exterior of the assembled box, I nail a ground strip (21) along the vertical joint 20 between the side wall sections, and to the top and bottom plates (5) and (7), this ground strip being narrower than the combined width of the interlocked framed sections, thereby permitting the edges of the outside 25 wall board (16) to over-lap and to be attached to the margin of the frame and the stop (14). This ground strip determines the thickness of the cement plaster or stucco coating (22), which is applied to the wall or 30 stucco board (16), and the joints are covered by a trim (23) along the sides, and by trim boards (24) and (25) at the corners. Any suitable quarter-round finishing (26) may be applied at the corners, and the cork filler 35 (27) is inserted in the square space left between the edges of the cork boards at the corners.

It will be observed that the projecting cork boards (13) will over-lap the bottom cork, 40 and under-lap the top cork, and that the filler strips (20) will provide a continuous inside wall of insulation, it being understood that the door is itself suitably insulated. Preferably the filler strips (20) are cut 45 slightly wider than the standard space left between the adjacent exposed edges of the cork sections (13), and in practice, I drive these filler strips (20) into place so that they will be held tightly in place by the resiliency 50 of the cork or insulating material. The inside walls of the refrigerator are preferably covered with a coating of plaster cement, which being supported throughout on the yieldable cork or insulation, is free to expand 55 and contract uniformly throughout and will not crack or check responsive to expansion and contraction.

It is important to know that in tearing down and re-assembling my refrigerator all 60 the insulating material is preserved in proper position in its supporting frame and is not lost, with the exception of the cork filler strips (20), the filler strip (27) being nailed to one or the other frames and coming down 65 with it intact. Thus my refrigerator is truly

portable and can be readily taken down and assembled, and enlarged and decreased in capacity as conditions require.

The side wall frames are aligned and secured to the bottom plate (5) and top frame 70 (7) by dowel pins (28), and lag screws (29), connect the top frame to the top side wall sections. The bottom rests free of attachment on its foundation, and thus the refrigerator does not become attached to the building, and will bridge any irregularities in the 75 floor or foundation.

It will be understood that the spirit and scope of my invention contemplates various 80 changes in the details of construction and arrangement of parts, which are comprehended within the appended claims.

What I claim is:

1. A refrigerator of the character described, comprising insulated top and bottom 85 sections and a plurality of knock-down wall sections, each section comprising a marginal frame; means to assemble the frames at the sides and corners; insulation mounted within each frame, and projecting inwardly therefrom, in position to make a lap joint with the insulation of the top and bottom sections; and means to connect the side wall sections to the top and bottom sections. 90

2. A refrigerator according to claim 1 in 95 which the bottom section comprises a marginal confining frame for the insulation which projects thereabove, said frame being adapted to support said wall section frames.

3. A refrigerator, according to claim 1, in 100 which the top comprises a marginal frame carrying overhead supports for the insulation mounted therein, which insulation underhangs said frame, and which frame is adapted to rest on the top of the said section frames. 105

4. A refrigerator comprising a bottom insulating section, and a plurality of side wall insulating sections, each comprising a marginal frame having insulation mounted within, and projecting inwardly therefrom; means 110 to assemble the side wall frames on the top and bottom sections, and filler strips of insulation adapted to fill the spaces between the cork in the side wall sections, and to insulate the frames thereof. 115

5. A refrigerator, according to claim 4, in 120 which the inwardly projecting insulation from the side wall sections is adapted to make a lap joint with the insulation of the top and bottom sections and said continuous inner surface of insulation is covered by a cement plaster coating.

6. A refrigerator comprising top and bottom insulated sections and a plurality of knock-down side wall sections, and means to assemble said side wall sections with the top and bottom sections, each side wall section comprising a marginal frame, and insulation confined therein, and projecting inwardly therefrom, the inner wall of said insulation 130

- being spaced from the outer surface of the frame, each frame carrying an outer plaster receiving surface, forming the outer wall of the confined air space provided between it and the insulation. 5
7. A refrigerator, according to claim 6, in combination with means to tie the abutting frames to each other. 7
8. A refrigerator, according to claim 6, in combination with ground strips mounted over the joints between the abutting side wall frames, and plaster applied to said plaster receiving surface within the marginal walls formed by said ground strips. 10
9. A refrigerator comprising a bottom formed of a marginal plate, inclosing insulation of greater thickness than the plate, a plurality of side wall sections, each comprising a marginal frame adapted to set on said plate; means to align and attach each side wall frame to said plate, each side wall frame inclosing insulation disposed to project inwardly therefrom, and leave a space between the insulation and outer surface of the frame, 15 and an outer plaster receiving wall attached to the frame, and forming a confined air chamber in each side wall frame; means to connect the side wall frames to each other; means to mount the insulated top on the side wall frames, and insulation filler strips interposed to fill the joints between the cork in the side wall frames. 20
10. A refrigerator, according to claim 9, in which the cork insulation in the top and bottom of the refrigerator projects sufficiently to make a butt joint with the over-hung insulation from the side wall frames and the interposed filler strips. 25
11. A refrigerator having its bottom formed by sheets of insulation adapted to rest on a suitable support, and a confining plate surrounding said insulation, and of less thickness than the insulation, in combination with the side walls and top, the side walls comprising frames adapted to be supported by and secured to the bottom plate, and carrying insulation adapted to over-lap the bottom insulation. 30

In testimony whereof I affix my signature.
JOSEPH E. TWITTY.
